INVENTOR;

THOMAS J. LITTLE, JR.,
BY *H. C. Little*

ATTORNEY.

UNITED STATES PATENT OFFICE.

THOMAS J. LITTLE, JR., OF DETROIT, MICHIGAN, ASSIGNOR TO CADILLAC MOTOR CAR COMPANY, OF DETROIT, MICHIGAN, A CORPORATION OF MICHIGAN.

MOTOR VEHICLE.

Application filed June 23, 1917. Serial No. 176,595.

To all whom it may concern:

Be it known that I, THOMAS J. LITTLE, Jr., a citizen of the United States, and resident of Detroit, Wayne County, State of Michigan, have invented certain new and useful Improvements in Motor Vehicles, of which the following is a specification.

This invention relates to hydrocarbon motors, and particularly to improvements in carbureting systems therefor.

One of the objects of this invention is to provide a carbureting system, which will efficiently produce a satisfactory explosive mixture for starting an internal combustion engine, and for maintaining it in operation under extreme climatic conditions.

Another object of this invention is to provide a simple and efficient means for maintaining the carburetor air supply and motor induction pipe at satisfactory temperatures.

I have discovered that the induction pipe of an internal combustion engine may be most efficiently heated by means of the exhaust gases, by connecting the jacket as a by-pass in the exhaust system, rather than by leading the exhaust gas into the jacket at one end and discharging it into the atmosphere at the other end. It is found that when the latter arrangement is used, the fluctuating pressure of the gas within the exhaust pipe will result in a partial vacuum in the heating jacket at times, thus causing cold air or air at the temperature of the atmosphere to be drawn in the jacket outlet.

I have also discovered that by connecting one port of the heating jacket to one part of the exhaust system, and connecting another port of the heating jacket to another part of the exhaust system, a surging action through the jacket is set up, the velocity of which will depend upon the frequency of the gas impulses within the exhaust pipe. In the preferred embodiment of my invention, I have used a U shaped gas induction pipe arranged between multi cylinder blocks mounted in V relation, with the opposite ends of the induction pipe connected with an inlet port to each of the blocks. Each block is provided with an exhaust manifold and the induction pipe jacket is provided with a pair of ports, each connected with one of the exhaust pipes. It will be noted that if this arrangement is applied to an eight cylinder, four cycle

motor, timed to fire alternately in opposite blocks, there will be four explosions each revolution, with two explosions in each block. This will result in the creation of two alternating periods of high and low pressure in each exhaust pipe per revolution; and with the heating jacket connected to each of the exhaust pipes, there will be a surging of exhaust gases through the jacket of the same frequency as the pressure variations. The heating effect on the induction pipe and its temperature for varying conditions may be controlled by regulating the amount of the surge by varying the communication of the jacket with the exhaust pipes. I have, however, discovered a remarkable constancy in ratio between the heat required by the incoming gas to maintain a given temperature and the heat in the gas discharged into the exhaust pipes. In other words, the heat regulation for varying throttle positions of the motor throttle is substantially automatic in this respect.

It will, of course, be understood that the novel discovery of the surging action in a by-pass of a motor exhaust system may be used for other heating purposes. Another object, therefore, of my invention is to provide a novel and improved internal combustion heating device, especially adapted for use in maintaining an element of an internal combustion engine at a desired temperature.

These, and various other objects will more clearly appear from the following description, taken in connection with the accompanying drawings which form a part of this specification, and in which:

Figure 1, illustrates an end elevation, with portions broken away, and others in section, of a V type multi-cylinder, four cycle, hydrocarbon motor, preferably having eight cylinders;

Figure 2 is a plan, diagrammatic view of 100 a carburetor, and a gas induction pipe applied to an internal combustion engine, according to my invention;

Figure 3 is a side elevation, with portions broken away, of my carburetor and 105 gas induction pipe unit; and

Figure 4 is a vertical section, substantially on the line 4-4 of Figure 3.

Referring to the drawings, 10 represents a crank case on which are arranged in V 110

relation, a pair of blocks 11, each preferably comprising four cylinders. Each block is provided with intake ports 12 and exhaust ports, one of which is illustrated in dotted line at 13 in Figure 1. The ports are adapted to be controlled by the usual poppet valve members 14 and cams 15 on a shaft 16, suitably mounted in bearings 17 of the crank case. The cylinders are of course provided with the usual pistons 18 and connecting rods 19, coupled with throws 20 of the crank shaft 21, suitably mounted in the crank case 10. A manifold 22 is arranged along a side face of each of the cylinder blocks 11 with its ports 23 in registry with the exhaust ports 13 of that block. The exhaust manifolds are adapted to be secured in position as by bolts 24.

A U shaped induction pipe 25 is arranged between the blocks with the ports 26 which are formed in its opposite ends, each in registry with a passage leading to the intake ports 12 of one of the cylinder blocks. This manifold is secured in position as by a bolt 27. The induction pipe is formed with a surrounding jacket 28, provided with hollow arms 29, each having a port 30 joined by a nipple 31 with the interior 32 of one of the exhaust manifolds 22. It will be understood that with an eight cylinder, four cycle motor having the ignition arranged to fire alternately in opposite cylinders, there will be two explosions in each block which will be exhausted into each of the exhaust manifolds 22, during each revolution of the crank shaft. This will cause two pulsations of exhaust gas through the jacket 28 in each direction during each revolution of the crank shaft. The surging effect of the gas and their heating action on the induction pipe 25 may be regulated by varying the communication of the jacket with the exhaust pipes.

I have shown mounted in each connecting nipple 31, a butterfly valve 33. A by-pass 34 is formed in the nipple around the valve, so that when it is in closed position, there is a restricted communication between the jacket and the exhaust manifold. This by-pass restriction may be varied by an adjustable screw 35. The butterfly valves 33 are each provided with an arm 36, which are connected by a link 37 and the valves are adapted to be simultaneously operated by means which will be described hereinafter.

The induction pipe 25 is provided intermediate its ends with an inlet port 38, over which is suitably arranged the outlet of a carburetor 39 which is secured in position as by bolts 40. The carburetor is provided with the usual fuel chamber 41, float valve mechanism 42 and a fuel nozzle 43, adapted to discharge as at 44, into the lower end of a Venturi tube 45.

Arranged between the fuel bowl 41 and

the mixing chamber 46 of the carburetor are a cover 47, and a diaphragm 48 for supporting the Venturi tube 45. The cover member is formed with upwardly extending lugs 49 which serve to space the cover from the diaphragm 48 and provide ports 50 therebetween. The ports 50 are circumferentially arranged around the cover member and connect the passage 51 with a housing 52 which surrounds these ports. A port 53, Fig. 4, is formed in the housing 52 for permitting the entrance of primary air into the interior of the carburetor, where it will mix with the fuel discharged from the jet 43.

A hood 54 having openings 55 is adapted to surround one of the exhaust pipes 22 in spaced relation thereto. The hood is provided with an outlet 56 which may be connected by a conduit 57 with the air port 53. It will be noted that the air drawn into the conduit must necessarily flow over the heated exhaust pipe into the hood 54, whereby the temperature of the air is raised considerably. For heating the primary air for starting purposes, before the exhaust pipe 22 has been raised to the desired temperature, I have inserted in the conduit 57, a pipe 58 preferably formed of a high resistance metal such as microme. This pipe is adapted to be insulated at one end as by bushing 59, from the conduit and may be grounded at its other end as at 60 on the primary air port nipple 61. An electrode 62 at one end of the resistance pipe 58 may be connected to a suitable source of current as by a conductor 63. I prefer to energize this heating unit just prior to starting the motor for drawing in heated air to volatilize the heavier oil such as kerosene, when the motor is turned over by the usual power driven starter. Of course, after the motor is in operation, the exhaust pipe will serve to heat the incoming primary air.

The main body of the carburetor is provided with a laterally extending portion 64 in the lower wall of which is formed an auxiliary air port 65, over which is arranged a flap valve 66 which is pivotally mounted on the chamber as by a trunnion 67. The valve 66 is adapted to be maintained normally closed by means of a spring 67' one end of which is secured to a lug 68 on the valve and the other end of which is connected under compression to the lower arm 69 of a choke operating device, which is trunnioned as at 70 on the auxiliary air valve chamber.

A thermostat comprising a flexible corrugated side wall 71, a movable end wall 72 and a relatively stationary end wall 73 is adapted to be filled with a volatile liquid such as ether. The lower end wall is formed with an opening in which is fitted a stand-pipe 74 having its lower end open to the interior of the thermostat and its upper end

is adapted to be connected with a branched tube 75 having the ends 76 of its opposite branches extending into the interior of the induction pipe 25. The thermostat is suitably housed and insulated from variations in temperature by a shell 77 and the tube 75 is also covered by a suitable insulation. The lower wall 73 of the thermostat is of course anchored by the connected tube 75 and any variations in the temperature within the induction pipe will cause an expansion or contraction of the liquid within the tube 75 and the thermostat. As the temperature rises, it will carry the wall 72 of the thermostat upwardly, with a like movement of a rod 77' which is connected therewith. This rod, which is adjustably connected as at 78 with one arm of a T shaped crank lever trunnioned at 79 on the carburetor, will at the same time, permit the end 80 of said T shaped lever to be pulled by the spring 80' and close the shutters 33 through the connecting link 37. It will also be noted that the T lever has the arm 81 which is adapted to be raised upwardly by an arm 82 of a bell crank trunnioned as at 83 and which is also provided with another arm 84 coupled by a link 85 with the auxiliary air valve choke device. The arrangement is such that when the air valve choke is operated to increase the compression of the auxiliary air valve spring 67, it will increase the opening of the shutters 33, which will of course increase the heating effect of the exhaust gases on the induction pipe 25. In other words, when the fuel mixture is enriched, the induction pipe temperature is simultaneously raised and provision is also made for thermostatically controlling this temperature.

While I have described and will specifically claim what I deem to be preferred forms of my invention, it will be obvious to those skilled in the art, that various modifications and changes may be made without departing from the spirit and scope hereof.

Having thus described my invention, what I claim and desire to secure by Letters Patent is:

50. 1. The combination with an internal combustion engine having an exhaust pipe, of a gas intake pipe provided with a heating jacket having a port, means for causing a part of the exhaust gas to flow alternately and in reverse directions through said port and into and out from said jacket; and thermostatically controlled means for regulating the flow of exhaust gas into and out from said jacket.

60. 2. The combination with an internal combustion engine provided with an exhaust system having different portions in which there occur simultaneously periods of relatively high and low pressure, of a gas induction pipe provided with a jacket having a

plurality of ports, connections between each of said ports and one of said portions, whereby a vibrant surging of gas is set up in said jacket, and thermally controlled means in each of said connections for regulating the flow of gas through said jacket. 70

3. The combination with an internal combustion engine having a plurality of exhaust elements in each of which alternately occur periods of high and low pressure, of a gas induction pipe provided with a jacket having ports arranged at its opposite ends and each connected with one of said elements, and thermostatic means for regulating the communication of each of said elements with 80 said ports.

4. The combination with an internal combustion engine having a plurality of exhaust elements in each of which alternately occur periods of high and low pressure, of a gas induction pipe provided with a jacket having ports arranged at its opposite ends and each connected with one of said elements, a carburetor connected with said induction pipe and having a mixture regulating device, and means connected with said device for regulating the communication of said elements with said ports. 85

5. The combination with an internal combustion engine having a plurality of exhaust elements in each of which alternately occur periods of high and low pressure, of a gas induction pipe provided with a jacket having ports arranged at its opposite ends and each connected with one of said elements, a carburetor connected with said induction pipe and having a mixture regulating device, thermostatic means for varying the communication of said elements with said ports, and means connected with 90 said device for regulating the communication of said elements with said ports, and independently of the operation of said thermostatic device. 95

6. In an internal combustion engine, the combination with a plurality of cylinder blocks arranged in V relation, each block being provided with an intake port and an exhaust port at its inner face, an exhaust manifold connected with the exhaust ports of each of said blocks, an induction pipe arranged between said blocks with its opposite ends connected with the intake ports of said blocks, said induction pipe being provided with a heating jacket having ports at its opposite ends each connected with one of said exhaust pipes, a carburetor connected with said induction pipe intermediate its ends, valve means for regulating the communication of said jacket ports with 115 said exhaust pipes, and thermostatic means for actuating said valve means. 120

7. In an internal combustion engine, the combination with a plurality of cylinder blocks arranged in V relation, each block 130

being provided with an intake port and an exhaust port at its inner face, an exhaust manifold connected with the exhaust ports of each of said blocks, an induction pipe arranged between said blocks with its opposite ends connected with the intake ports of said blocks, said induction pipe being provided with a heating jacket having ports at its opposite ends each connected with one of said exhaust pipes, a carburetor connected with said induction pipe intermediate its ends, valve means for regulating the communication of said jacket ports with said exhaust pipes, and thermostatic means for actuating said valve means, said thermostatic means being adapted to be affected by variations of temperature within said induction pipe.

8. In an internal combustion engine, the combination with a plurality of cylinder blocks arranged in V relation, each block

being provided with an intake port and an exhaust port at its inner face, an exhaust manifold connected with each of said blocks in communication with the exhaust port thereof, an induction pipe arranged between said blocks with its opposite ends connected with the intake ports of said blocks, said induction pipe being provided with a heating jacket having ports at its opposite ends, each connected with one of said exhaust pipes, a carburetor connected with said induction pipe intermediate its ends, valve means for regulating the communication of said jacket ports with said exhaust pipes, thermostatic means for actuating said valve means, a mixture regulating device for said carburetor, and an inter-connection between said device and said valve means for operating the device and valves simultaneously.

In testimony whereof I affix my signature.

THOMAS J. LITTLE, JR.
